Primary Examiner—Celia Murphy*Attorney, Agent, or Firm*—Senniger, Powers, Leavitt & Roedel[57] **CLAIM**

The ornamental design for a sport shoe outsole, as shown and described.

DESCRIPTION

FIG. 1 is a bottom plan view of a sport shoe outsole of the present invention;

FIG. 2 is a right side elevational view thereof;

FIG. 3 is a left side elevational view thereof; and,

FIG. 4 is a perspective view thereof.

The midsole of the sole illustrated in phantom forms no part of the design.
